[57] **CLAIM**

The ornamental design for a perfume bottle having the shape of a flower, as shown and described.

DESCRIPTION

FIG. 1 is a perspective view of a perfume bottle having the shape of a flower showing my new design;

FIG. 2 is a top view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.

The broken line showing of the spray pump is for illustrative purposes only and forms no part of the claimed design.
